SCAFFOLDING

John P. Biebel, Belleville, Ill.

Application January 20, 1936, Serial No. 59,813

10 Claims. (Cl. 304—18)

My invention relates to scaffolding, and embodies improvements over my co-pending application Serial Number 23,067, filed May 23, 1935.

An object of my invention is to provide a scaffolding having an upper and a lower platform suspended from a series of single cables wound upon hoisting drives so carried by scaffolding frames that the scaffolding will be self balancing when materials and workmen are thereon.

10 Another object of the invention is the provision of a scaffold frame member and built in hoisting drive mechanism therefor which is light, simple and durable in construction, separable as to sections thereof, and highly efficient for the purpose designed.

With the above and other objects in view, which will be clearly apparent hereinafter, the invention consists in the novel features of construction, arrangement and combination of parts hereinafter fully described and finally pointed out in the claims hereto appended.

Referring to the accompanying drawings forming a part of this specification, wherein like characters of reference denote similar parts throughout the several views:

Fig. 1 is a side elevation of a scaffold frame embodying the features of my invention.

Fig. 2 is a view of the scaffold frame looking in direction of the arrow in Fig. 1.

30 Fig. 3 is a fragmentary plan view of a scaffold embodying the features of my invention.

Fig. 4 is a view of the hoisting drive, with one half of the hoisting drive housing removed and the cable-drum and its actuating means in sectional elevation.

In carrying out the invention, I employ a suitable U-shaped frame section designated, generally, as 1, and upon the cross-member 2 thereof a walk plank, or platform 3 is adapted to be supported. The upper end of the upright rear arm 4 of the U-shaped frame is provided with a suitable loop, or holder 5 by means of which a suitable guide rail 6 is supported when passed therethrough.

45 Disposed above the U-shaped frame 1 and offset to the front thereof, is a triangularly shaped frame section designated, generally as 7. The rear end of the lower horizontal arm 8, of the frame section 7, is secured to the upper end of the front vertical arm 9 of the U-shaped frame section 1 and to a depending arm 10 of a hoisting drive housing designated, generally, as 11, by means of a suitable fastening device such, for instance, as a bolt 12. The depending housing arm 10 can be L-shaped, if desired, and se-

cured to the horizontal arm 8 of the frame section 7 by means of a second fastening device such, for instance, as a bolt 13. This arrangement enables the lower frame section 1 to be readily detached from the upper frame section 7, and assembled as quickly. This knock-down arrangement permits the scaffold frame to be transported knocked-down, if desired, and packed in a relatively small space.

The horizontal arm 8 of the upper frame section 7 serves as a support adjacent to the upper end of the U-shaped frame section 1 and to the front thereof, or in offset relation thereto, and serves as means for supporting a platform of plank 14 upon which materials can be laid for easy access to workmen standing on the walk platform 3, thus obviating the necessity of workmen bending to reach the material and tools to be used by them as the platform is within easy reach in front of them without their bending over, thus the efficiency of the workmen on the scaffold is greatly increased.

The upper frame section 7 includes a short front vertical portion 15 terminating in an upwardly and rearwardly inclined portion 16, and, which in turn terminates at its upper end in a downwardly projecting vertically disposed arm 17 which terminates short of the rear end of the horizontal arm portion 8 of the upper frame section 7. This provides a gap in the rear portion of the upper frame section which is taken up by the hoisting drive housing 11. The lower end of the upper frame section arm 17 is detachably secured to an upstanding arm 18 on the upper side of the hoisting housing 11 by means of a suitable fastening device such, for instance, as a bolt 19.

A suitable cable guiding sleeve 20 is suitably secured to the rear face of the vertical depending arm 17 of the upper frame section 7 through which a single suspended hoisting cable 20' passes, as will be clearly apparent hereinafter.

40 A suitable bracing member 21 connects the hoisting drive housing 11 with the inclined front portion 16 of the upper frame section 7 and its front end is suitably secured to the frame portion 16 by a suitable fastening device such, for instance, as a bolt 22.

The lower and upper frame sections 1 and 7, respectively, can be formed of suitable light weight angle-iron, or other shaped material which will afford sufficient stiffness and rigidity to the frame structure when assembled.

50 The hoist drive housing 11 is shown in one embodiment thereof as consisting of two sections,

a rear section 23 and a front section 24 suitably secured together by suitable fastening devices such, for instance, as screws 25, 26 and 27. The arms 18 and 19 on the housing 11 preferably, 5 although not necessarily, project from the rear housing section 23, as shown, so that the longitudinal axis of the housing will lie approximately in alignment with the front edges of the members 9 and 17 of the lower and upper frame sections 10 1 and 7, respectively, which provides a properly balanced frame when in use.

Disposed within the hoisting drive housing 11 is a suitable flanged cable-drum embodying a hub 28 having spaced flanges 29, a worm gear 30 secured 15 to one end of the cable-drum by suitable fastening means 31, a worm 32 meshing with the worm gear 30. The cable drum hub 28 is greater in diameter than the supporting shaft 33 which passes through openings 34 in the ends to be supported 20 at opposite ends in suitable recessed bearings 35 formed in opposed walls of the hoisting drive housing. Surrounding the shaft 33, are a series of roller bearings 36 which pass into the drum hub openings 34 at each end of the drum, 25 thus leaving the cable-drum free to rotate relative to the roller bearings 36 and the roller bearings free to rotate relative to the shaft 33. One end of the drum hub 28 is provided with an extension of reduced diameter to serve as a centering guide 30 in positioning the worm gear relative to the cable drum.

The worm 32 has a shaft 37 projecting from both ends thereof journaled in bearings formed by an opening 38 and a recess 39 in opposite walls 35 of upper portions of each half of the hoisting drive housing which is shaped, as at 40, to accommodate the worm 32. The shaft 37 at one end of the worm 32 passes through the opening 38 and the other end of the shaft is merely journaled in 40 the recess 39.

The free rear end of the shaft 37 is provided with a removable head 41 secured in position by means of a set screw 42. The head is provided with a suitable transverse opening 43 through 45 which passes a suitable lever 44 secured in adjusted position relative to the head 41 by means of a suitable fastening device 44 and the lever 44 is provided with a suitable handle 45.

A suitable stop lever 46 is suitably pivoted to the 50 upper frame section 7, as at 47, and the device projects rearwardly, when in operative position, as shown in full lines in Fig. 1, so as to lie in the path of travel of the lever 44, thus serving as a safety device to prevent any possible chance of 55 the worm being rotated, accidentally or otherwise, beyond the stop lever 46. The stop lever 46 can be moved upwardly and forwardly into a position adjacent portion 16 of the upper frame section 7 when it is desired to actuate the hoisting 60 drive for either raising or lowering the scaffold and be moved back into safety position again after having raised or lowered the scaffold.

The housing 11 of each hoisting drive, it will be observed, is provided with a suitable opening 48 through which the cable passes to be wound upon and unwound from the cable-drum disposed within 65 the housing 11.

A pair of brace members 49 are secured to the arms 4 and 8 of the U-shaped frame section 1 by 70 means of fastening devices 50. The brace members 49 are inclined upwardly and forwardly and project beyond the arm 4 of the U-shaped frame section 1 and suitably connected at their front ends to a pair of spaced arms 51 secured to and 75 depending from the rear end of the arm 8 of the

triangularly shaped frame section 7, as clearly shown in Fig. 1. A suitable guide wheel 52 is rotatably supported between the arms 51 by means of a shaft 53 supported by the arms 51. The guide wheel 52, it will be observed, is adapted 5 to ride on the wall of a building when raising and lowering a scaffold. It will be observed that the guide wheel is disposed adjacent the lower front corner of the triangular frame section 7 and to the front of the U-shaped frame section 1, as 10 clearly shown in Fig. 1.

It is apparent that any number of scaffold frames suitably spaced apart can be employed in erecting a scaffolding in order to support the desired number of walk boards and material 15 supporting boards which serve as platforms, as is manifest.

In order to retard longitudinal swinging movements of the scaffolding when suspended in operative position adjacent the wall of a building, 20 I find that by employing a suitable guide cable or rope 54 connected at its upper end to the support to which the hoisting cable 20 is connected and suitably anchored at its lower end to the ground, and by passing the guide rope 25 through a pair of eyebolts 55 secured to the upper and lower ends of each scaffold frame, that this arrangement limits movement of the scaffolding away from the building wall due to the guide rope being anchored at its lower end 30 to the ground.

The many advantages of the herein described invention will readily suggest themselves to those skilled in the art to which it appertains.

From the foregoing description, it is evident 35 that a simple device for this purpose has been disclosed, but it is to be understood that I do not desire to restrict, or limit myself to the very details of the construction shown and described, which is merely illustrative, it being obvious that 40 changes, not involving the exercise of invention, may be made without conflicting or departing from the spirit of the invention within the scope of the appended claims.

What I claim is:

1. A suspending scaffold side frame comprising 45 a lower U-shaped frame member, a hoisting mechanism housing, means for securing one end of the U-shaped frame member to the lower end of the housing, a triangularly shaped frame member disposed above and in front of the U-shaped housing, a cable guide sleeve secured to the rear upper end of the triangularly shaped frame member, means for securing the rear lower end of the triangularly shaped frame member to the housing, means for securing the opposite end of the triangularly shaped frame member to the upper end of the housing, spaced 50 bearings depending from the forward lower end of the triangularly shaped frame member, a 55 guide wheel rotatably supported by the bearings, and bracing members connecting the bearing members with the U-shaped frame member.

2. A suspending scaffold frame having, in combination, a lower U-shaped frame member 60 adapted to support a walking plank, an upper triangularly shaped frame member disposed to the front of and above the U-shaped frame member and secured at one end thereto and adapted to support a work supporting plank adjacent the front upper end of the U-shaped frame member, and a hoisting mechanism disposed at the lower rear corner portion of the 65 triangularly shaped frame member.

3. A structure as defined in claim 2 wherein 70

a guide wheel supporting means is carried adjacent the lower front corner of the triangularly shaped frame member, and bracing members connecting the guide wheel supporting means 5 with the U-shaped frame member.

4. A suspending scaffold side frame having, in combination, a U-shaped walking plank supporting frame member, a triangularly shaped working material plank supporting frame member 10 disposed in front of the U-shaped frame member adjacent the upper end thereof, a guide rail supporting loop carried by upper rear end of the U-shaped frame member, a guide wheel, guide wheel supports depending from the front lower 15 corner of the triangularly shaped frame member, bracing members connecting the U-shaped frame member with the guide wheel supports, a cable guide sleeve secured to the upper end of the triangularly shaped frame member, a separable 20 housing carried by the triangularly shaped frame member and manually actuated hoisting mechanism enclosed within the housing.

5. A structure as defined in claim 4 wherein the hoisting mechanism includes a rotatable 25 cable carrying drum, a worm gear rotatable therewith, a worm in mesh with the worm gear, a shaft connected handle for manually actuating the hoisting mechanism, and a lever pivotally connected to the triangularly shaped frame 30 member to prevent accidental rotation of the said handle.

6. In a scaffold frame structure, a U-shaped walking plank supporting frame member, a triangular working material supporting frame 35 member disposed above and in front of the walking plank frame member and secured thereto, a guide wheel disposed adjacent the front lower corner of the working material supporting frame member, a hoisting mechanism housing carried 40 by the rear side of the working material supporting plank frame member, and a hoisting cable guide sleeve secured to the upper rear end of said latter frame member.

7. In combination with a scaffold frame having 45 means for supporting a platform to walk upon and a platform to support material used by workmen and which platforms are one above the other in offset relation, of a hoisting drive housing having a cable opening therein, a cable-drum within 50 the housing, a shaft supporting the drum and

journaled at its ends in bearings formed in opposite walls of the housing, roller bearings intermediate the shaft and the cable-drum whereby rotary movement of each is independent of the other, a worm gear secured to one end of the 5 cable-drum, a worm meshing with the worm gear, and means for manually rotating the worm to actuate the worm gear and cable-drum as a unit.

8. A cable suspended scaffold comprising a plurality of scaffold frames each having an upper 10 triangular section and a lower U-shaped section, working material supporting planks on the upper section portion, walking planks on the lower U-shaped sections, said upper triangular sections being disposed to the front and above the U- 15 shaped sections, a hoisting mechanism carried by the triangular section of each scaffold frame, vertically spaced eyelets at the upper and lower ends of said triangular and U-shaped sections respectively, through which guide ropes pass. 20

9. A scaffold frame having, in combination, a lower U-shaped main walk plank supporting frame member, an upper triangularly shaped frame member having a gap in one section thereof and disposed above the front section of the U- 25 shaped frame member, the base of the upper frame section being disposed to the front of the upper end of the front section of the U-shaped frame member, a hoisting drive housing closing the gap and secured to both the U-shaped frame 30 member and the triangularly shaped frame member, the lower end of the triangularly shaped frame member adapted to support a plank utilized for supporting working material disposed in front of working men, an elongated cable guide 35 sleeve secured to the rear section of the triangularly shaped frame member and at the upper end thereof, a brace member connecting the hoisting drive housing with the front section of the triangularly shaped frame member, cable hoisting 40 mechanism including a crank carried by the housing, and a lever pivotally secured to the rear section of the upper frame member adapted to serve as a stop for the hoisting mechanism crank.

10. In a device as defined in claim 9, including 45 spaced eyelets secured to the upper and lower ends of the triangular and U-shaped frame members, respectively, for guiding a scaffold guide cable passing therethrough.

JOHN P. BIEBEL. 50
